INVENTOR,

Ralph Tucker,
BY William J. Gluck
ATTORNEY.

UNITED STATES PATENT OFFICE

2,087,074

BUTTON

Ralph Tucker, Larchmont, N. Y.

Application August 17, 1936, Serial No. 96,343

4 Claims. (Cl. 24—113)

This invention relates in general to buttons and in particular to ornamental buttons. While I have shown my invention as applied to a conventional shirt button it is to be understood that it is not intended to be limited to that particular type of button, but may be applied to buttons of all types, and as to certain phases thereof, it may have other applications than to buttons. Buttons embodying the invention of this application may be used on uniforms, military livery, and the like, which ornamentation may bear appropriate insignia.

Among the objects of my invention is the provision of a button consisting of two members one of which may be directly attached to the garment or other article to which it is to be applied, and the other member of which is ornamental in character, and is adapted for removable attachment to the first member.

Among other objects of my invention are the provision in a button of an ornamental member that may be readily attached thereto and removed therefrom, and may be used interchangeably with other buttons, the provision of a member that may be applied to a button so as to hide the securing threads passing through the button, the provision in a two part button, of means for securing one of said parts to the other in such a way that it cannot be readily displaced, and is not at all displaceable by pressure upon the outer face thereof.

For the attainment of these objects and such other objects as may hereinafter appear or be pointed out I have shown an illustrative embodiment of my invention in the drawing, in which:

Figure 1 is a plan view of a button constructed according to my invention; and

Figure 2 is a sectional view on the line 2—2 of Figure 1, looking in the direction of the arrows.

Referring now to the drawing in detail, I have there illustrated a button comprising two parts, one of which, A, is in its main outlines of the conventional shirt button type such as is customarily made of pearl and having button holes 110 therein, and I have further shown a part B adapted for association with the part A. The part B is shown as ornamental in character, and I have indicated a letter C as applied in relief thereto, whereby is suggested the use of the ornamental insert for displaying the initials of a wearer.

It will be observed that while the exterior outline of the portion A is of the conventional shirt button type, that I have shown the central portions thereof sunk in or recessed to a greater ex-

tent than is customary, as shown at R, and the side walls of the button-holes are shown as being undercut or tapered upwardly as indicated at 112 in Figure 2.

The portion B is shown as of circular contour and of upwardly convex configuration, with prongs 116 projecting therefrom, and these prongs are shown as bent or bellied outward and as provided with an outwardly inclined base or root portion and an inwardly bent free tip portion. 10

The inwardly bent tip portions will serve to guide the prongs 116 into the button-holes 110 when the parts A and B are brought together into the proper relation, and are pressed against each other, the prongs 116 being bent inwardly during 15 this process. When the parts are in their final assembled relation, as shown in Figure 2, the prongs 116 will again move outwardly, due to their resilience and will engage the undercut portions 112 as a result of which the parts A and B will 20 be held in assembled relation.

In Figure 2 I have indicated the fabric of a garment at 124, and numeral 126 indicates the threads for serving to secure the button to the fabric, these threads passing through a pair of 25 button holes, as customary. It will be observed that the space between the parts A and B is sufficient to accommodate the threads, so that the latter offer no resistance to the insertion of the part B into the part A. It will be understood 30 that for the purpose of obtaining more space to accommodate the thread 26, the depth of the recess in the button may be increased, while the member B may be made more convex than shown, with the same end in view.

By viewing Figures 1 and 2 it will be seen that when the parts A and B are assembled, that in appearance as well as in effect they constitute a unit, and to enhance this effect the parts A and B may be made as shown, that is relatively contoured so that their outer surfaces merge. By 40 reason of the separability, however, great variety of finish and the use of different materials is made possible.

Further advantages will now also be apparent. 45 The engagement of the two parts is such that it is impossible to dislodge the part B from its seat within the part A by pressure externally applied to either of these parts. In fact the only way such separation may be effected is by inserting 50 an instrument such as a pin or a piece of wire through one of the button holes and pressing against the inner wall of the part B so as to force it outward. When therefore the garment is subjected to laundering operations there is prac- 55

tically no possibility of their becoming separated. By making sure that the outer walls of the insert B are sunk below the adjacent walls of the part A, the insert B is still more effectively protected against removal. Such a construction is indicated in Figure 2.

Another advantage lies in the enhanced ornamental appearance of the button due to the arrangement whereby the button, in which the securing threads are ordinarily exposed, and which is therefore unsightly, becomes highly ornamental because the securing threads are effectively hidden from view by an ornamental element, which also additionally serves to protect the threads against damage.

An outstanding advantage of my invention is that feature thereof which permits a manufacturer of garments, such as shirts, to deliver to a distributor a garment, conventional in type except that the buttons thereof will be of the type herein disclosed. The ornamental feature may then be either added or omitted at the option of the purchaser, without impairing the attractiveness of the garment. The wearer of a garment to which my buttons are applied will have the satisfaction of having his initial or initials appear on the garment, so as to identify it with the wearer, or may have an emblem, motto, campaign slogan or other features associated therewith. The dealer in garments on the other hand will stock his garments as heretofore mentioned with buttons having the insert B omitted therefrom, so that he is prepared, with a minimum amount of stock, to provide the customer with a garment in which the ornamental feature is omitted from the buttons, or with one to the buttons of which any desired initial, emblem or other ornamental feature is applied.

While only two prongs 116 have been indicated and this number is obviously sufficient for the proper securing together of the parts, it will be clear that any desired number may be used, it being understood of course that appropriate button holes, suitable in number and position, are provided in the button. It should be remembered, however, that the button holes may exceed the prongs in number.

I have found that where the button is of pearl and the ornamental insert is made of metal, that a very effective ornamental combination may be produced. The insert for example may have the letter or other ornament thereon gold plated, so as to stand out from the background, which may be coated with enamel of any desired color. However, it will be obvious that other materials may be found equally suitable, and for

certain purposes even more desirable. It would be superfluous to mention any particular ones among such materials. It will further be understood that while I have described prongs for effecting the securing action, that other forms of securing members may be used, and that while the prongs 116 have been described as depending for their action on their inherent resiliency, that such property is not essential, as their snapping into place may be secured by other means. For certain purposes, too, it may be found to be desirable to make the prongs or other securing means so that they can be readily given a permanent deformation as where, for instance, they are made of soft metal.

While I have herein disclosed one illustrative embodiment of my invention it is to be understood that it may be embodied in many other forms, as will be obvious to those skilled in the art, without departing from the spirit thereof, and that the disclosure herein is intended to be by way of illustration merely, and that I do not limit myself in any way other than as called for by the prior art.

Having thus described my invention and illustrated its use, what I claim as new and desire to secure by Letters Patent, is:—

1. A button provided with perforations adapted to receive a securing thread, a cap adapted for association with said button and having portions thereon adapted to pass into said perforations and to hold said button and cap together against separation.

2. A button provided with perforations adapted to receive a securing thread, a cap adapted for association with said button and having resilient portions thereon adapted to pass into said perforations and to hold said button and cap together against separation.

3. A button provided with perforations adapted to receive a securing thread, said perforations having undercut walls, a cap adapted for association with said button and having portions thereon adapted to pass into said perforations and to engage said undercut portions thereof, and to hold said button and cap together against separation.

4. A button provided with perforations adapted to receive a securing thread, said perforations having undercut walls, a cap adapted for association with said button and having resilient portions thereon adapted to pass into said perforations and to engage said undercut portions thereof, and to hold said button and cap together against separation.

RALPH TUCKER.
